(57) **CLAIM**

The ornamental design of a distributed control system module-mounting base, substantially as shown and described.

DESCRIPTION

FIG. 1 is a front and left side perspective view of a distributed control system module-mounting base in accordance with the present invention;

FIG. 2 is a front and right side perspective view of the distributed control system module-mounting base in FIG. 1; FIG. 3 is a front elevation view thereof;

FIG. 4 is a top plan view thereof;

FIG. 5 is a right side elevation view thereof;

FIG. 6 is a left side elevation view thereof;

FIG. 7 is a bottom plan view thereof; and,

FIG. 8 is a rear elevation view thereof.

The features shown in broken lines in the various Figs. are for illustrating environmental structure and form no part of the claimed design.
